SWINGING DOOR

Joseph Lucchino, 1351 N. Ogden Drive,
Los Angeles, Calif.

Filed Dec. 22, 1959, Ser. No. 58,765

Term of patent 14 years

(Cl. D13—1)

Fig. 2.

I claim:

The ornamental design for a swinging door, as shown.
